UNITED STATES PATENT OFFICE

2,607,962

WINDOW STRUCTURE

Alvin J. Baumann, Reedsville, Wis.

Application May 12, 1950, Serial No. 161,556

5 Claims. (Cl. 20—53)

1

This invention relates to new and useful improvements in window structures and the primary object of the present invention is to provide a window structure including a plurality of outwardly swingable closure members together with a manually actuated lever for simultaneously raising all of said closure members.

Another very important object of the present invention is to provide a window structure including a group of unitarily swinging closure members and a means for retaining or locking the closure members in a selected raised position and against accidental closing.

A further object of the present invention is to provide a window structure composed of a plurality of outwardly swinging closure members with the adjacent horizontal edges of adjacent members being rabbeted to permit interlocking of adjacent members when they are in their closed position.

A still further aim of the present invention is to provide a window structure that is quickly and readily assembled or disassembled in a convenient manner, and which is neat and attractive in appearance, strong and durable in use, simple and practical in operation, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front view of the present invention, partly in elevation and partly in section;

Figure 2 is a side elevational view of Figure 1 and with dotted lines showing the closure members raised to their maximum position and the actuating lever lowered to its maximum position;

Figure 3 is a longitudinal vertical sectional view taken substantially on the plane of section line 3—3 of Figure 1, and with dotted lines showing the closure members raised; and,

Figure 4 is a fragmentary group perspective view showing the manner in which the closure members are mounted on the frame and also the manner in which the connecting bars are attached to the closure members.

Referring now to the drawings in detail, wherein for the purpose of illustration, there is disclosed a preferred embodiment of the present invention, the numeral 10 represents a window frame composed of a pair of vertical side rails 12 and 14 having upper and lower grooves 16 and 18 in their inner faces and adjacent their ends that receive the ends of upper and lower cross rails 20 and 22.

A plurality of closure members or window

5 sashes 24 are associated with the frame and are mounted upon the frame for vertical swinging movement in a manner now to be described. The ends of the closure members 24 are provided with recesses 26 that receive anchor plates 28. The plates 28 are held in the recesses 26 by fasteners 30 that extend through the plates and into the ends of the closure members.

10 The plates 28 are located relatively close to the upper edges of the closure members and the plates 28 hold the reduced threaded inner ends of horizontally projecting trunnions or pivots 32 having splined outer ends 34.

15 The side rails 12 and 14 are provided with vertically spaced horizontal openings 36 in each of which there is fitted a bearing sleeve 38. The sleeves 38 rotatably support the trunnions 32 and the ends 34 of the trunnions project outwardly from the side rails 12 and 14 to enter splined 20 openings 40 in the enlarged ends 42 of connecting arms 44. Set screws 46 threaded in the ends 42 bear against the ends 34 of the trunnions to hold the arms 44 on the trunnions.

25 The adjacent horizontal edges of adjacent closure members are rabbeted, as at R, to permit interlocking of adjacent closure members when the closure members are moved to their closed position as shown in Figure 3.

30 The lower most of the openings 36 in the side rails are located below and parallel to the cross-rail 22 and the bearing sleeves 38 therein rotatable support a strengthening rod or rock shaft 48 whose splined ends project from the rails 12 and 14 to support lower arms 45 similar to the arms 44.

35 A connecting bar 50 is pivoted, as at 51, to each of the arms 44 that are mounted on the trunnions projecting through the rail 12 and to the arm 45 on one end of the shaft 48. Another connecting bar 52 is pivoted, as at 54, to each of the arms 44 that are mounted on the trunnions projecting through the rail 14 and to the arm 45 on the other end of the shaft 48.

40 An actuating lever 54 is pivoted, as at 56, to the rail 12 at a conveniently accessible position and is attached to the bar 50 by a horizontal pivot 58 so that a lowering of the lever 54 will effect a raising of the bar 50, directly, and will cause the closure members and the bar 52 to also be raised. The opening in the lever 54 through which the pivot 58 extends is sufficiently large as to permit the lever to be manually urged horizontally or laterally of the rail 12 and the bar 50 for a purpose later to be described.

45 The free upwardly curved end portion 60 of the lever 54 supports a finger grip or knob 62 which permits a convenient handling of the lever during raising or lowering of the closure members.

50 Means is provided for locking the closure mem-

bers in a selected raised position, and this means comprises a vertically disposed guide and retainer member 64 that is secured by fasteners or the like to the inside trim of the window 12. The flange 66 is provided with a plurality of vertically spaced recesses or notches 68 for selectively receiving the lever 54 and a vertical slot 69 is provided in the trim T to prevent the lever from springing out of place.

The upper rail 20 supports a horizontal sealing strip 70 that will contact the upper rabbeted edge of the uppermost closure member when the latter is in its closed position, and the lower rail 22 supports a lower sealing strip 72 that will contact the lower rabbeted edge of the lowermost closure member when the lowermost closure member is in its closed position, as shown in Figure 3, to properly seal the closures to the frame and to each. Obviously additional vertical resilient sealing strips may be applied to the inner faces of the rails 12 and 14 to close the slight space between the ends of the closure members and the rails 12 and 14.

The rails 12, 14, 20 and 22 are provided with ribs 14 to which there is secured a screened frame member 76. The frame member 76 is readily removed and may be replaced by a storm sash during cool weather.

The recesses 26 extend to the upper edges of the sash so that when the sash is open, the fasteners 30 may be removed and the sash slipped from the plates 28 without having to remove any other parts.

The sash may be easily cleaned from the inside of the building by simply removing the screen. Also, the window structure is of an awning type that will provide full ventilation as well as reflecting the sun out of the room. Furthermore, the sash may remain open during a windstorm.

Additionally, there are no rods, bars or anything to obstruct the view through the sash nor is there anything to collect dust or mar its beauty except one small knob used for opening and closing the sash.

Having described the invention, what is claimed as new is:

1. A window structure comprising an open frame, a plurality of vertically swinging closure members mounted on said frame, connecting means between all of said members for simultaneous swinging movement of all of the members, a lever pivoted on said frame and also pivoted to said connecting means and manually actuated to simultaneously raise said closure members, and means carried by the frame and engaging said lever to retain the closure members in a selected raised position, said lever engaging means including an angle member having vertically disposed flanges, one flange of said angle member having a plurality of vertically spaced notches for selectively receiving said lever.

2. A window structure comprising an open frame including a pair of vertical side rails and a sill, a plurality of closure members within said frame and including ends paralleling said rails, anchor plates secured to the ends of said closure members, horizontally projecting trunnions secured to said plates and extending through said rails, a first connecting bar pivotally attached to the trunnions projecting through one of said side rails, a second connecting bar pivotally attached to the trunnions projecting through the other side

5 rail, a rock shaft on the frame underlying the sill and pivotally connected to both bars, a lever pivoted to the frame and also pivoted to the first bar to permit simultaneous raising of all of said closure members, and means mounted on the frame and engaging said lever to retain the closure members in a selected raised position.

3. A window structure comprising an open frame including a pair of vertical side rails, a plurality of closure members within said frame and including ends paralleling said rails, anchor plates secured to the ends of said closure members, horizontally projecting trunnions secured to said plates and extending through said rails, each of said trunnions having an outer splined end projecting from said rails, connecting arms having splined openings receiving the splined ends of said trunnions, a first connecting bar pivoted to the arms on the trunnions extending through one side rail, a second connecting bar pivoted to the arms on the trunnions extending through the other side rail, a rock shaft mounted on the frame and paralleling the trunnions and connected to both bars, and means pivotally mounted on one of the vertical side rails of the frame and pivotally connected to one of said bars intermediate the ends of the latter for simultaneously raising said closure members.

4. A window structure comprising an open frame including a pair of vertical side rails, a plurality of closure members within said frame and including ends paralleling said rails, anchor plates secured to the ends of said closure members, horizontally projecting trunnions secured to said plates and extending through said rails, each of said trunnions having an outer splined end projecting from said rails, connecting arms having splined openings receiving the splined ends of said trunnions, a first connecting bar pivoted to the arms on the trunnions extending through one side rail, a second connecting bar pivoted to the arms on the trunnions extending through the other side rail, a rock shaft on the frame paralleling the trunnions and pivoted to both bars, an actuating lever pivoted on said frame and also pivoted directly to said first bar for raising said closure members, and a vertical retainer on said frame adjacent said first bar and including a flange having a plurality of vertically spaced notches for selectively receiving said lever to retain the closure members in a selected raised position.

5. The combination of claim 2 wherein the ends of said closure members are provided with recesses receiving said anchor plates to permit the ends of said closure members to be disposed relatively close to said side rails.

ALVIN J. BAUMANN.
